UNITED STATES PATENT OFFICE.

THOMAS NORWOOD ARNOLD, OF FAIRPORT, NEW YORK.

TOY.

1,415,292.

Specification of Letters Patent.

Patented May 9, 1922.

Application filed December 23, 1920. Serial No. 432,733.

To all whom it may concern:

Be it known that I, THOMAS N. ARNOLD, a citizen of the United States, residing at Fairport, in the county of Monroe and State 5 of New York, have invented certain new and useful Improvements in Toys, of which the following is a specification.

This invention relates to toys, the primary object of which is to provide a propelled toy, 10 the movement of which causes the simultaneous action of figure toys, which in this instance, simulates a clown riding on a mule.

Another object of the invention is to provide a toy of simple construction, which is 15 positively operable so as to selectively cause movement of different parts of the figures in harmony with the movement of the element upon which they are mounted, producing an amusing spectacle which can be used without 20 danger of injury to children playing with the same.

The above and other objects of the invention will be in part described and in part understood from the following description 25 of the present preferred embodiment of the invention taken in connection with the accompanying drawings, wherein:

Fig. 1, is a side elevational view of a toy constructed in accordance with this invention, a portion thereof being broken away to 30 disclose details.

Fig. 2, is a horizontal sectional view showing the base in top plan.

Fig. 3, is a fragmentary rear elevational 35 view partly in vertical section to show details of the mechanism.

Fig. 4, is a sectional view taken on the line 4—4 of Fig. 3, looking in the direction of the arrow, and

Fig. 5, is a detail fragmentary side elevational view of the device showing to advantage the automatic movement of the mechanism of the upper figure when the lower figure moves.

In the drawings, a base 6 is provided 45 which is preferably arranged in a horizontal plane and of an oblong shape. The front of the base is mounted upon a frame 7, the latter being carried by an axle which extends between and is connected to a pair of wheels 8. The axle is in turn connected by a handle 9 through the medium of which the base is propelled. The rear end of the base 50 is bifurcated as indicated at 10 and has an

axle 11 arranged through the branches of 55 the bifurcation adjacent the free terminals thereof.

A wheel constituting a driver 12 is mounted upon the axle 11 between the branches of 60 the bifurcation and spaced from the latter by means of sleeves 13 which are rotatable upon said axle and carry pendulums or weights 14. Each side of said driver is equipped with an abutment or stop 15 so as to limit rotary movement of said pendulums 65 in a manner which will be subsequently apparent.

Arranged upon the base 6 is a figure 16, which in this instance, constitutes the representation of a mule, the front feet of which 70 are secured, as indicated at 17, upon the branches of the bifurcation at the rear of the base. The upper ends of the legs 18 are pivotally mounted upon the body of the mule as indicated at 19. The rear legs 20 of the 75 mule are adapted to engage the top of the base 6 adjacent the front end of the latter. The rear or hind legs are not secured to the base other than by means of a cable 21, one end of which is connected to a cross-bar 22 80 which extends between said legs, while the opposite end is secured to the top of the base. In this way limited arcuate movement of the hind legs will be permitted through the arc described by the letter A. 85

Depending from the neck of the mule, in close proximity to the head thereof, are a pair of rods 22, each of which has one end thereof pivotally connected to said neck, while the opposite end is bifurcated and the 90 branches of the bifurcation straddle a shaft 23 and are secured thereto. The shaft 23 carries a pair of discs 24 which normally lie on opposite sides of the wheel 12 as shown in Figs. 1 and 2. It will thus be seen that movement of the base 6 will cause the wheel 12 to be rotated which correspondingly imparts movement to the pendulums 14 until either of the latter rides to the top of the wheel, following which the pendulum gravitates 100 into engagement with either one of the discs 24, thereby pulling downwardly on the rods 22. This causes the head of the mule to be correspondingly pulled downwardly which elevates the rear end of the mule to the extent 105 of the cable 21.

Superimposed on the top of the mule, preferably at the rear end of the latter, is a

figure representing a clown generally designated 25. The body of the clown is supported upon the mule by a standard 26, as illustrated in Fig. 1. The body of the toy 5 may be of any desired design, but is tubular and is equipped with pivoted legs 27 and arms 28. The inner end of each arm and leg is preferably of a circular configuration and equipped in each instance with a strap 10 29. One end of the strap is engaged with the periphery of the disc and the opposite end engaged with a vertically extending rod 30. The legs 27 have the lower ends thereof pivoted at the knees as indicated at 15 31, consequently reciprocatory movement of the rod 30 will cause the legs to be bowed outwardly to simulate gymnastic maneuvers performed by bare back riders and the like. It is likewise apparent that when the rod 30 20 imparts movement to the arms 28, causing the latter to pass through the arcs defined by the dotted lines B.

The rod 30 extends downwardly through the mule, preferably between the rear legs 25 20 of the latter, and terminates in an opening formed in the cross-bar 22. An abutment 32 is formed upon said rod 30 adjacent the lower end of the latter in order to limit downward movement of the rod when the 30 rear end of the mule is elevated as illustrated to advantage in Fig. 5. In order to cause downward movement of said rod a weight 33 is provided, which is preferably located between the hind legs 20 of the mule so that 35 as the latter moves upwardly the weight will gravitate causing the rod 30 to move downwardly in an obvious manner.

It will be apparent from the above that when the handle 29 is pulled initial movement 40 will be imparted to the mule, which correspondingly permits movement of the clown. Continued movement of the base will restore both the mule and clown to their normal position, since the pendulum after 45 having struck one of the discs 24 will gravitate downwardly to release pressure from the neck of the mule, thereby permitting the latter to gravitate back into position, which action causes the lower projected end of the

rod 30 to strike the top of the base 6, and thereby elevate said rod.

Various changes may be made in this invention, especially in the configuration of the figures used and the manner of positioning the same. In the present instance, the clown 55 is shown as facing the operating end of the base so as to be visible at all times to the operator of the handle 9. Changes may likewise be made in the details of construction, proportion and arrangement of parts within 60 the scope of the appended claims.

What is claimed is:

1. A toy including a base, one end of which is equipped with a driver wheel, a figure mounted upon said base, a pendulum operable by movement of said driver to lower one end of said figure and raise the opposite end thereof, and means carried by said figure and automatically movable by the elevation of one end thereof to describe various phases 70 of movement.

2. A toy including a base equipped with a driver wheel, pendulums associated with said driver wheel and operable by movement thereof, a figure mounted upon the base and 75 equipped with means lying in the path of movement of said pendulums, whereby the figure is operated by movement of the driver, a second figure mounted upon the first said figure and automatically movable by the 80 latter to perform a series of different movements.

3. A toy including a movable animal figure, means to automatically lower one end of said figure and raise the opposite end 85 thereof when the figure is moved in its entirety, and a representation of a human figure mounted upon said animal figure and automatically movable by actuation of the latter to cause movement of the arms and 90 legs of said human figure.

In testimony whereof I affix my signature in presence of two witnesses.

THOMAS NORWOOD ARNOLD.
